UNITED STATES PATENT OFFICE.

ALEX G. BIONDI, OF LOS ANGELES, CALIFORNIA.

SAFETY DEVICE FOR MINES.

1,292,236.

Specification of Letters Patent. Patented Jan. 21, 1919.

Application filed September 6, 1918. Serial No. 252,962.

To all whom it may concern:

Be it known that I, ALEX G. BIONDI, a subject of the King of Italy, residing at Los Angeles, in the county of Los Angeles and State of California, have invented new and useful Improvements in Safety Devices for Mines, of which the following is a specification.

My object is to make a safety device for mines, and my invention consists of the novel features herein shown, described and claimed.

Specifically an object of my invention is to automatically disconnect a cage after it passes the upper landing and avoid the possibility of the cage being carried too high and wrecked by the overhead obstructions. Figure 1 is a side elevation showing a mine shaft extending above the ground and provided with a safety device embodying the principles of my invention, parts being broken away and shown in section.

Fig. 2 is a fragmentary side elevation at right angles to Fig. 1, and looking in the direction indicated by the arrow 2.

Fig. 3 is a horizontal section on the line 3—3 of Fig. 1.

Fig. 4 is an enlarged front elevation of the safety device as seen looking in the direction indicated by the arrows 4 in Figs. 1 and 5.

Fig. 5 is a side elevation of the safety device looking in the direction indicated by the arrow 5 in Fig. 4, parts being broken away and shown in section.

Fig. 6 is a fragmentary sectional detail on the line 6—6 of Fig. 5.

Fig. 7 is a horizontal cross section on the line 7—7 of Fig. 5.

Fig. 8 is a vertical sectional detail on the lines 8—8 of Figs. 5 and 7.

Fig. 9 is a horizontal sectional detail on the line 9—9 of Fig. 5.

Fig. 10 is a diagram showing the operation of the safety device.

The mine shaft 1 extends downwardly from the face 2 of the ground 3, and the posts 4, 5, 6 and 7 extend upwardly from the face 2 of the ground, the posts being arranged in the form of a rectangle in plan, and a guide rail 8 is mounted between the posts 4 and 5, and a similar guide rail 9 is mounted between the posts 6 and 7. The cage 10 has guideways 11 and 12 fitting the posts 8 and 9, so that the cage will travel up and down in the shaft 1 and between the

posts 4, 5, 6 and 7 above the ground and in line with the shaft. The upper cage landing 13 is some distance above the ground, and it is desirable that automatic means be provided to prevent the cage 10 from going more than a slight distance above the landing 13. The guide pulley 14 is mounted upon the posts 5 and 7 above a platform 15, and the cable 16 runs over the pulley 14 and downwardly through the platform 15. A clevis 17 is connected to the end of the cable 16 by looping the cable through the clevis and forming the fastening 18. The safety device 19 is connected to the clevis 17 by the clevis pin 20. The lifting stem 21 extends upwardly from the center of the top of the cage 10, and a lifting head 22 is fixed upon the upper end of the stem. The safety device 19 serves to connect the cable 16 to the cage 10 by engaging the lifting head 22.

The details of the safety device 19 are as follows:

The main frame consists of the horizontal base 23, the substantially vertical arm 24 extending upwardly from one end of the base 23, the inclined arm 25 extending upwardly from the other end of the base 23, the upper ends of the arms 24 and 25 being joined, and the eye 26 extending upwardly from the joined ends of the arms 24 and 25 to fit between the bearings of the clevis 17 and receive the clevis pin 20. A vertical opening 27 is formed through the base 23 to receive the lifting head 22, and a slot 28 extends from the opening 27 toward the arm 24 to receive the lifting stem 21, there being a flat face 29 around the slot 28 to support the lifting head 22.

A latch bar 30 is mounted upon the base 23 and slides through an opening 31 in the arm 25, there being roller bearings 32 under the latch bar 30, and the latch bar serves to cover the opening 27 and engage the head 22 to hold the head 22 upon the supporting face 29 when it is desired to lift the cage 10. A stop 33 is mounted upon the latch bar 30 to engage the arm 25, so that when the latch bar 30 moves outwardly to bring the stop 33 into engagement with the arm 25 the opening 27 is uncovered to allow the head 22 to pass through the opening 27. Roller bearings 34 are recessed into the supporting face 29 under the head 22, so that the head will move easily. A latch lever 35 is placed against the outer inclined face of the arm 25. A housing plate 36 is placed

2

in front of the latch lever 35, and a pivot 37 is inserted through the housing plate 36 through the latch lever 35 and tapped into the arm 25, so that the latch lever may 5 swing downwardly in front of the latch bar 30 and may swing laterally out of the way of the latch bar 30. A lug 38 extends forwardly from the upper end of the arm 25 and the housing plate 36 fits against this lug 10 and is secured in place by screws 39. The lower end of the housing plate 36 is bent backwardly to form the attaching plate 40 which extends under the base 23 and is held in place by cap screws, thereby forming a 15 chamber 41 in which the latch lever 35 operates freely. An opening 42 is formed through the housing plate 36 for the latch bar 30. A retractile coil spring 43 is connected to the latch lever 35 and to the frame, 20 the tension of the spring being exerted to pull the latch lever 35 into normal position to hold the latch bar 30 to hold the supporting head 22 to lift the cage 10. An arm 44 extends upwardly and outwardly from the 25 latch lever 35. A trip base 45 is secured to a cross bar 46 inserted between the posts 4 and 6, and a trip 48 extends from the trip base 45 to engage the arm 44 as the safety device goes upwardly, and a second trip 47 30 extends from the base 45 to engage the incline face 49 of the housing plate 36, so that as the safety device goes up carrying the cage 10, the trip 48 will first engage the arm 44 and move the latch lever 35 out of engagement with the latch bar 30 and then 35 continued upward movement will cause the trip 47 to slide upon the face 49 and deflect the safety device 19 and tilt the base 23, thereby causing the lifting head 22 to move 40 upon the rollers 34 until the head 22 falls through the opening 27, thereby disconnecting the cage 10 from the cable 16.

In this way it is made impossible for the cage 10 to be moved upwardly against the 45 platform 15 or the other overhead machinery. Heretofore it has sometimes happened that the cage was pulled up through the roof of the landing and wound around the pulley 13 and caused more or less damage and endangered the lives of any one who 50 might be in the cage. By the use of the safety device 19 the cage will pass upwardly above the landing 13 and will be automatically disconnected to fall back upon the 55 supports 50 and 51. Of course, if the cable 16 is properly operated the cage will only pass above the supports 50 and 51 and then back up and rest upon the supports. It is only intended that the safety device will

operate as a safety device when other safety means fail.

It is obvious that my safety device may be used in mines having inclined or horizontal shafts as well as in vertical shafts.

Various changes may be made without departing from the spirit of my invention as claimed.

I claim:

1. A safety device comprising the combination with a cage having a supporting stem and a supporting head upon the stem, of a base having an opening to receive the head and a slot to receive the stem; a latch bar slidingly mounted upon the base to cover and uncover the opening; an inclined face 70 extending upwardly from the base; means for connecting the base to the elevating cable; latch mechanism for controlling the latch bar; and trips adapted to be rigidly mounted for operating the latch mechanism 75 and for engaging the inclined face. 80

2. A safety device comprising the combination with a cage elevated by a cable and having a supporting stem and a supporting head upon the stem, of a base having an opening to receive the head and a slot to receive the stem, a latch bar slidingly mounted upon the base to cover and uncover the opening, an inclined face extending upwardly from the base, means for connecting the 85 base to the elevating cable, a latch controlling the latch bar, a stationary trip adapted to engage said latch and move the same out of engagement with said latch bar, a spring tending to move said latch into a normal 90 latch bar engaging position, a second stationary trip adapted to engage the inclined face after said first named trip has engaged said latch whereby the latch bar is caused to uncover the opening and the head is 95 caused to pass therethrough. 100

3. A safety device for a cage elevated by a cable comprising a stem connected to the cage and a supporting head upon the stem, a base having an opening to receive the head 105 and a slot to receive the stem, means for locking the head to the base, means for releasing said locking means, means operating said releasing means when the cage goes beyond the desired point and means operative 110 after said last named means for tilting said base to cause said head to move through said opening by gravity thereby disengaging the cage from the safety device.

In testimony whereof I have signed my 115 name to this specification.

ALEX G. BIONDI.
